SOUTHERN PRISON COMPANY, OF SAN ANTONIO, TEXAS, A CORPORATION OF TEXAS

MASTER CONTROL CABINET FOR JAIL DOOR OPERATING SYSTEMS

Application filed July 6, 1931. Serial No. 549,043.

This invention relates to master control cabinets for jail door locking and operating systems and, among other objects, aims to provide an improved counterbalanced, slideable door panel for inset cabinets so arranged as to afford easy and quick access to the operating mechanism.

Other aims and advantages of the invention will appear in the specification, when considered in connection with the accompanying drawings, wherein:—

Fig. 1 is a front elevation of a control cabinet having the preferred form of door applied thereto;

Fig. 2 is a sectional view, taken on the line 2—2 of Fig. 1;

Fig. 3 is a view similar to Fig. 2 but showing the door open;

Fig. 4 is a sectional view taken on the line 4—4 in Fig. 1;

Fig. 5 is a sectional view taken on the line 5—5 in Fig. 1; and

Fig. 6 is a sectional view taken on the line 6—6 in Fig. 2.

Master control cabinets for jail doors are usually arranged at the end of a row of cells in a jailer's corridor which is separated from the prisoner's corridor. The jailer's corridor is sometimes quite narrow to economize with floor space. Heretofore, it has been customary to provide swinging doors for such cabinets. It has been found that such doors not only obstruct the passageways when they are open, but also present some hazards to a jailer in case of mutinies. In some instances, the corridor space is too narrow to permit swinging a door open. This invention provides a vertically sliding door assembly adapted to be built in a control cabinet and so constructed that it requires no extra space in which to open, and which can be opened and closed very quickly but cannot be easily tampered with by prisoners.

Referring particularly to the drawings, the preferred form of door is shown as being installed in a rectangular control box 10 which is usually placed at the end of a row of cells. This box is preferably secured with its back against a corridor wall 11 so that the wall constitutes an operating panel 12 for a mas-

ter hand wheel 13 and selector levers or buttons 14 for controlling the doors.

In this example, the side and end walls of the control box are made of channel beams 15 and 16, respectively, whose rear flanges 55 are secured to the panel or rear wall 12. The front flanges 17 of the channels 15 extend inwardly and are utilized as front guides for a pair of vertically slideable door panels 18 and 19, preferably made of tool-proof metal. 60 Sheet metal panels 20 and 21 are secured to the front flanges at the top and bottom respectively, Fig. 1, so that door panels will slide behind them when the door is opened. These fixed panels are preferably reinforced at the edges adjacent to the door opening, by steel strips 22 secured on both the outside and inside of said panels.

To provide rear guides for the sliding door panels, a pair of structural angles 23 70 are shown as being secured to the inner faces of the webs of the side channels 15 and have guide flanges 24 spaced from the inside of the channel flanges 17 (Figs. 1 and 2). In this instance, both door panels lie in the same 75 vertical plane so that their edges abut each other when they are closed. Both door panels are shown as having narrow vertical strips 25 secured to them behind the bevelled inside faces of the channel guide flanges 17. 80 However, filler strips might be welded on the flanges instead. The upper door panel preferably has a pair of transverse strips 26 secured to its lower edge between the inner edges of the guide flanges 17 and projecting 85 below the edge of the panel to provide a receiving groove for the upper edge of the lower panel 19 when the door is closed. This prevents a prying tool from being inserted between the abutting edges of the panels. Angle brackets 27 carrying an ordinary handle bar 28 are shown as being secured to the outer strip 26, so that the upper door panel may be 90 opened by grasping the handle and raising it.

The door panels are connected to move in unison and are counterbalanced, the mechanism being so arranged that it does not obstruct the opening. In this instance, the lower door panel has an inverted, U-shaped 100

frame consisting of side strips or members 29 secured to the inside of the door panel at the opposite edges to work in the guides 24, 17 and these strips 29 project above the upper edge of the lower panel a height slightly greater than the height of the door opening, being connected by a transverse strip 30 at the top.

On this strip 30, at the center or above the center of gravity of the lower door is secured a short, inwardly projecting bracket 31 to which one end of a sprocket chain 32 is secured. The chain is trained over a sprocket 33 and its other end is secured to an inwardly projecting bracket 34 on the lower edge of the upper door panel 18. The bracket 34 extends inwardly of the box farther than the bracket 31 so that the inner run or flight of the chain 32 will hang vertically and substantially parallel with the outer run. The arrangement is such that when a little lifting force is applied to the handle 28 on the upper door panel, both panels will open simultaneously, the lower one opening by gravity. Upon closing the upper panel the lower panel will be raised by the sprocket and chain.

Both doors are adapted to be locked when closed so as to prevent unauthorized tampering with the operating mechanism. In this example, a lock 35 of the sliding bolt type is secured to the inside of the lower panel 19 at one side and a keeper 36 conveniently in the form of an angle bracket having an opening in one flange is secured to the guide member 23 (Fig. 5). The locking bolt is adapted to be projected into the opening by a key. On the lower inside edge of the upper door panel, there is shown a locking bracket 37 secured on a spacer block 38 and having a bolt-receiving hole in a vertical flange 39. This bolt opening is adapted to register or be aligned with the keeper opening so that the locking bolt will pass through both of them. The lock is thus concealed with the box so that it cannot easily be broken.

To prevent trash from dropping into the bottom of the box, there is shown a partition 40 secured to the rear wall 12 at the bottom of the door opening. Also, a narrow shelf or partition 41 is secured to the wall near the upper part of the door opening. These partitions also serve to prevent prisoners from jamming the door panels or the connections between them. The lower partition has an opening 42 into which the lock 35 may move when the lower door panel is open. The upper shelf or partition also has a notch or opening 43 for the chains 31 and bracket 34.

From the foregoing description, it will be seen that the control box or cabinet and the door assembly can be built as a unit ready to be installed. The door panels require no outside or extra space in which to be opened. The counterbalanced panels permit them to

be quickly opened and closed with very little effort. There are no exposed parts which are easily broken. All of the parts are easy to assemble and can be made at a very reasonable cost.

Obviously, the present invention is not restricted to the particular embodiment thereof herein shown and described. Moreover, it is not indispensable that all the features of the invention be used conjointly, 75 since they may be employed advantageously in various combinations and subcombinations.

What we claim is:

1. A master control cabinet for jail door 80 operating systems having vertical guides at the opposite sides; a pair of slidable door panels mounted in said guides; and counterbalancing connections between said panels which insure movement of the panels simultaneously in opposite directions when opened and closed; said counterbalancing connections being such that the opening into the cabinet is entirely unobstructed when both panels are wide open.

2. A master control cabinet for jail door operating systems comprising, in combination, channel beams forming the side walls and so arranged that the flanges on one edge provide front door guide members; rear 85 guide elements secured to the webs of said beams; fixed upper and lower panels secured to the beams defining a door opening in front of the operating mechanism; a pair of door counterbalanced panels slidably mounted in the guides; and a lock arranged to lock both panels in closed position.

3. A master control cabinet for jail door operating systems comprising, in combination, channel beams forming the side walls 105 and so arranged that the flanges on one edge provide front door guide members; rear guide elements secured to the webs of said beams; fixed upper and lower panels secured to the beams defining a door opening in front of 110 the operating mechanism; a pair of door counterbalanced panels slidably mounted in the guides; a handle on one door panel; and a lock on the other panel arranged to lock both panels in closed position.

4. In a master control cabinet of the class described, vertical guide members at the opposite sides; a pair of slidable door panels mounted in the guides; brackets on the inside of said panels; a sprocket wheel above 120 the centers of said panels; and a chain trained over said sprocket connected to said brackets.

5. In a master control cabinet of the class described, side walls having vertical guides; fixed upper and lower front panels defining a door opening; a pair of sliding door panels in said guides, one above the other; a frame connected to the lower panel and extending upwardly above the upper edge of the door 130

opening; a sprocket in the upper portion of the cabinet above the centers of said panels; and a sprocket chain trained over said sprocket and connected at one end to the upper end portion of said frame and, at the other end, to the lower edge of the upper door panel.

6. In a master control cabinet of the class described, side walls having vertical guides; 10 fixed upper and lower front panels defining a door opening; a pair of sliding door panels in said guides, one above the other; a frame connected to the lower panel and extending upwardly above the upper edge of the door 15 opening; a sprocket in the upper portion of the cabinet above the centers of said panels; a sprocket chain trained over said sprocket and connected at one end to the upper end portion of said frame and, at the other end, 20 to the lower edge of the upper door panel; a handle on the lower edge of the upper panel; a lock on the lower panel; a fixed keeper for the lock at one side of the cabinet; and a locking flange on the upper panel 25 adapted to register with the fixed keeper so as to lock both panels closed.

7. In a master control cabinet of the class described having vertical door guides at the opposite sides and fixed front panels defining 30 a door opening; a pair of counterbalanced door panels mounted in said guides; sheet metal plates on the edge of one panel adapted to overlap the edge of the other panel when the panels are closed; a lock for both of the 35 panels; and partitions in the cabinet adjacent to the upper and lower ends of the door opening.

In testimony, that we claim the foregoing as our own, we have hereto affixed our signatures.

J. K. MARDICK.
